UNITED STATES PATENT OFFICE.

EDWARD A. FISHER, OF WORCESTER, MASSACHUSETTS.

CASTANET.

SPECIFICATION forming part of Letters Patent No. 237,850, dated February 15, 1881.

Application filed December 4, 1880. (Model.)

To all whom it may concern:

Be it known that I, EDWARD A. FISHER, of Worcester, in the county of Worcester and State of Massachusetts, have invented a new and Improved Castanet, of which the following is a full, clear, and exact description.

The object of this invention is to provide an improvement on the well-known "bones" or "clappers" that are made to produce musical sounds on being held between the fingers and struck together, by making them more musical.

The invention consists of two pieces or strips of wood, the longer of which has an aperture made through it from side to side, near its lower end, and an insulated plate of metal secured over said aperture, while the shorter piece of wood has a ball, preferably of wood, attached by a rigid shank to its lower end, the castanets being operated by holding them between the fingers of one hand and striking the ball against the metal plate.

Figure 1 is a perspective view, showing the castanets in position in the hand. Fig. 2 is a front elevation of that part to which the metallic plate is secured. Fig. 3 is a vertical sectional side elevation of the same on line x x, Fig. 2. Fig. 4 is a front elevation of that part to which the ball is attached.

Similar letters of reference indicate corresponding parts.

In the drawings, A represents a strip of wood, designed to be about seven inches long, one inch wide, and one-quarter inch thick, having a rectangular aperture, a, made through it from side to side, near its lower end, and having, also, two holes, b b, made through it, above said aperture a, and two holes, c c, made through it, below said aperture a, through which holes b c is passed a strip or piece of yarn, felt, or like material, B, in such a manner as to form parallel lines on either side of the aperture a, from the holes b to the holes c, for the metallic plate C to rest upon, said yarn B being tied or otherwise conveniently secured in place. The plate C is held in place over

the aperture a by screws or pins d, that pass through said plate C into the wooden strip A, and said screws d are wrapped with yarn f, or other non-vibrating substance, to prevent the transmission of the vibrations of the plate C to the wooden strip A, or from the strip A to the plate C, the purpose of the yarns B f both being to so insulate the plate C from the strip A that the resonant vibrations of the former shall not be interfered with by the latter.

The other part of the castanet consists of a shorter piece of wood, D, narrowed at its lower end, and having secured thereto and in the same plane therewith, by a screw, g, a screw-eye, E, or other rigid shank, that extends beyond the extremity of the said piece D, and has screwed on its end a ball, F, preferably of wood.

When the parts A D are held between the fingers, as shown in Fig. 1, and the ball F is struck against the plate C, a musical sound is thereby produced, so that an expert in handling the castanets can play any tune thereon.

Having thus described my invention, I claim as new, and desire to secure by Letters Patent—

1. As an improved article of manufacture, a castanet, constructed substantially as herein shown and described, consisting of perforated strip A, having metallic plate C secured upon it, and strip D, having an attached ball, F, arranged as set forth.

2. In castanets, the combination, with the strip A, of the metallic plate C, substantially as herein shown and described, whereby the musical qualities of the castanets are improved, as set forth.

3. In castanets, the combination, with the strip A, provided with aperture a and holes b c, of the yarn B and plate C, arranged substantially as and for the purpose described.

EDWARD A. FISHER.
